ADJUSTABLE BLIND AND CURTAIN SUPPORT

Joseph Trimarchi and Lazzaro Pezza, Bronx, N. Y.

Application September 4, 1948, Serial No. 47,922

3 Claims. (Cl. 211—103)

1

This invention relates to an adjustable blind and curtain support.

It is an object of the present invention to provide an adjustable blind and curtain support wherein the bracket parts can be held by a latch in an elevated position. The latches for the respective brackets are capable of being pulled from one side of the window while the ropes for effecting the lifting of the brackets after they have been released and lowered also extend to the same one side of the window. The end of the ropes extending to the bracket at the said side of the window is extended through an extra pulley to make easier the lifting of the brackets at that side of the window and to provide a mechanical advantage in the connection.

Other objects of the present invention are to provide an adjustable blind and curtain support including brackets slidably adjusted at the opposite sides of the window and having control ropes located at one side of the window, which is of simple construction, easy to install upon the window frame, easy to operate and adjust, durable and sturdy, have portions adapted to receive any type of curtain or blind and efficient in operation.

For other objects and for a better understanding of the invention, reference may be had to the following detailed description taken in connection with the accompanying drawings, in which

Fig. 1 is a front elevational view of the brackets separated from one another and with the ropes or cords connected thereto and extending downwardly from one of the brackets at the one side and with portions broken away to show more clearly certain of the parts thereof.

Fig. 2 is a fragmentary and sectional view, in elevation, taken on line 2—2 of Fig. 1.

Fig. 3 is a sectional view, in elevation, taken on line 3—3 of Fig. 1.

Fig. 4 is a diagrammatic perspective view showing the arrangement of the ropes upon the pulleys and their connections with the latches and with the brackets.

Referring now to the figures, the description will be directed to one of the bracket constructions, but it will be understood that such description may apply to the other bracket located at the opposite side of the window and that the numerals applied to one may well apply to the other. 10 represents a rod which is connected to the side of the window. For this purpose, a bracket 11 is secured to the lower end of the rod as by welding and this bracket has vertically

2

extending lugs 12 with openings therein to receive the screws which can be extended into the window frame to support the lower end of the rod. On the upper end of the rod there is fixed an inverted channel 13 having outstanding lugs 14 with openings therein also adapted to receive screws for fixing the channel and upper end of the rod support 10 to the upper part of the window frame. These screws are indicated at 15 in Fig. 2 and are shown extended into a window frame 16.

Slidable on the rod support 10 is a long sleeve 17 to which is fixed a bracket plate 18 having angle bends 19 and 20 at the opposite sides of the same. To the angle bend 19 there is fixed a bracket plate 21 adapted to extend forwardly and at right angles to the plate 18. The upper edge of the plate 21 has different size notches 22 and 23 in its upper edge to receive respectively different diameter rod supports for curtains. The plate 21 can be removed and a different type of plate secured thereto. This plate is secured to the angle bend 19 by top and bottom screws 24 and 25. To the bend 20 which extends in the opposite direction from the bend 19 and inwardly into the top of the window frame, there is connected a special bracket 26 having a flange 27 of U shape and adapted to support the extension of a Venetian blind or pull curtain. The bracket 26 is connected to the bend 20 by nuts and bolts as indicated at 28 and 29 extending respectively through horizontally extending and vertically spaced slots 31 and 32. Accordingly, the brackets 26 can be extended inwardly to different distances depending upon the depth of the window frame.

In order to facilitate the extension of the projections on the blinds into the U-shaped flange 27, there is provided a continuation of the flange extending horizontally and as indicated at 33 to temporarily support the blind and to thereafter guide the blind projections when the blind is drawn outwardly into the U-shaped flange 27.

Also on the plate 26 is a dog leg slot 34 for receiving certain types of curtain rolls. On the plate 18 there is fixed a curtain rod bracket 35 having parallel upstanding projections 36 at the opposite sides of the same. This bracket 35 is fixed to the bracket plate 18 by screws 37.

On each plate 18 there is pivotally connected, as at 38, a latch 39 having a projection 41 adapted to extend through a slot 42 in the sleeve 17 for engagement with a slot 44 in the rod 10 whereby the bracket construction will be supported upon the rod 10 in the elevated position.

The projection 41 has an inclined upper edge to permit the free upward movement of the bracket but upon the slots 42 and 44 becoming aligned with one another, the projection 41 will enter these slots automatically and prevent the downward displacement of the bracket. In order that the brackets can be adjusted to different elevated positions, there are provided other openings as indicated at 45 in the rod support 10. When the latch 39 is pulled outwardly and made free of the slots 42 and 44, the bracket can be lowered on the rod 10.

To effect the operation of the latch, there is provided on the latch 39 on the bracket A at the left side of the window a small cord 46 which extends upwardly and over a pulley 47 journaled on the top channel 13 and across the top of the window over pulley 48 and pulley 49 on the channel 13 associated with the bracket indicated generally at B and at the right side of the window. The cord extends down to provide a loop 51 and then upwardly and over pulleys 49 and 48 and downwardly as indicated at 52 for connection with the latch 39 of the bracket B. By pulling either side of the loop 51, either one of the latches 39 of the respective brackets A and B can be operated or by pulling the entire loop 51 both latches can be operated simultaneously.

A similar system for the lifting of the brackets is provided. A larger rope is anchored to the channel 13 of the A bracket arrangement as indicated at 54 and extends downwardly over a pulley 55 journaled on the plate 18 of the A bracket arrangement and then upwardly over pulley 47 of the channel 13 and along the top of the window over the pulleys 48 and 49 of the channel 13 of the B bracket arrangement and then downwardly to form a loop 51. The cord extends upwardly from the loop and is returned over pulleys 49 and 48 and then downwardly and anchored to a projection 58 on the plate 18 of the bracket B. By pulling either side of the loop 57 either one of the brackets A or B can be operated singly or by pulling the entire loop both brackets can be lifted together. To lower the brackets, the loops 57 and 51 are pulled downwardly. Upon pulling downwardly upon the loop 57 the brackets can be elevated sufficiently to release the latch 39 and by returning the pull on the loop 51, these latches will be prevented from interfering with the downward movement of the brackets.

With the brackets in their lowered positions and at the lower ends of the rod supports, the curtains and the blinds can be readily removed from the brackets as the same will be placed within easy reach of the operator from the floor.

It should be apparent that there has been provided bracket arrangements for supporting blinds and curtains in an adjustable manner so that easy access can be had to the same for effecting their removal and wherein the brackets can be adjusted either singly or simultaneously by ropes located at one side of the window and depending from one bracket, the ropes being extended across the window for connection with the other bracket. By having the extra pulley 55 on the bracket A, a mechanical advantage is obtained in effecting the elevation of the bracket A. The

bracket A will be drawn upwardly on the rope and will be suspended by pulley 55.

While various changes may be made in the detail construction, it shall be understood that such changes shall be within the spirit and scope of the present invention as defined by the appended claims.

We claim:

1. A bracket arrangement for an adjustable blind and curtain support comprising a vertically extending support rod, a sleeve adjustable upon the rod, a bracket plate fixed to the sleeve and extending parallel to the window, said bracket plate having oppositely bent portions, a supporting plate connected to one of the portions and extending outwardly beyond the window, a second supporting plate connected to the other bent portion and adapted to extend into the window frame, an inverted channel secured to the top of the rod support, a pulley journaled in the channel and adapted to receive a cable cord.

2. A bracket arrangement for an adjustable blind and curtain support comprising a vertically extending support rod, a sleeve adjustable upon the rod, a bracket plate fixed to the sleeve and extending parallel to the window, said bracket plate having oppositely bent portions, a supporting plate connected to one of the portions and extending outwardly beyond the window, a second supporting plate connected to the other bent portion and adapted to extend into the window frame, an inverted channel secured to the top of the rod support, a pulley journaled in the channel and adapted to receive a cable rod, and said plate adapted to extend into the window frame being adjustably secured to the bent portion.

3. A bracket arrangement for an adjustable blind and curtain support comprising a vertically extending support rod, a sleeve adjustable upon the rod, a bracket plate fixed to the sleeve and extending parallel to the window, said bracket plate having oppositely bent portions, a supporting plate connected to one of the portions and extending outwardly beyond the window, a second supporting plate connected to the other bent portion and adapted to extend into the window frame, an inverted channel secured to the top of the rod support, a pulley journaled in the channel and adapted to receive a cable cord, and said plate extending into the window frame having a U-shaped flange extending laterally therefrom and a horizontally extending flange extending to one side of U-shaped flange and serving to guide projections of a blind or curtain into the U-shaped flange.
